UNITED STATES PATENT OFFICE.

TOM WILLIAMS, OF PILOT, WYOMING.

DISH-WASHING MACHINE.

1,289,588.

Specification of Letters Patent. Patented Dec. 31, 1918.

Application filed July 24, 1918. Serial No. 246,524.

To all whom it may concern:

Be it known that I, TOM WILLIAMS, a citizen of the United States, residing at Pilot, in the county of Fremont and State 5 of Wyoming, have invented certain new and useful Improvements in Dish-Washing Machines, of which the following is a specification.

This invention relates to a dish washing machine and has for its object to provide 10 a device of this character which shall be of simple construction, contain few parts, and which will force the water within the receptacle over the dishes contained therein 15 and wash them thoroughly.

A further object of the invention is to provide a dish washing machine with a receptacle for the dishes and the water for 20 washing the same with an inclined bottom 25 which will cause the water to gravitate to one side of the receptacle and mount therein to be covered by the water a pair of pump cylinders, the pistons of which are operated by a handle on the outside of the receptacle 25 whereby the water is drawn into the cylinders through perforations in the walls thereof and forced outwardly and upwardly through the same perforations to be distributed over the dishes within the receptacle.

With these objects in view, together with others which will appear as the description proceeds, the invention resides in the novel formation, combination and arrangement of parts, all as will be described more fully hereinafter, particularly pointed out in the claims, and illustrated in the accompanying drawings, in which:—

Figure 1 is a side elevation of the improved dish washing machine, a portion being shown in section.

Fig. 2 is an end elevation of the dish washing machine and,

Fig. 3 is a detail perspective view of one 45 end of one of the pump cylinders.

In the drawings, 10 indicates a receptacle for dishes, here shown as made of box-like form with an open top fitted with a cover 11 and having an inclined bottom 12 that extends 50 from one side of the receptacle to the other with an upward inclination as shown in Fig. 2, the lower or acute angle formed by the bottom and one side at 13 resting directly upon the support for the washing machine, the opposite side being sustained by legs 14 fastened to the ends of the re-

ceptacle 10. Within the receptacle and extending cross wise of the same at the center of its length is a stand 15 which serves to divide the receptacle into two parts and also 60 serves as a support for the dishes when placed in the machine to be washed.

Within the receptacle at the lower or acute angle 13 are mounted two pump cylinders 16, said cylinders, being each pivoted 65 at one end to the end of the receptacle so as to swing vertically. The opposite end of each cylinder is fitted with a removable head 17 through which passes a piston rod 18 on the inner end of which is a piston 19. 70 Through the top of each cylinder 16, at each end, is formed a hole 21 through which water passes into the cylinder when the piston is moving to the opposite end and out of which it is forced when the piston moves toward 75 the perforation. The piston rods 18 of the two pumps are pivotally connected to the lower end of a swinging arm 20 hinged at 22 to the side of the casing 10 near the top thereof and extending through the casing is 80 connected to a handle 23 that projects above the top of the washing machine in position to be grasped by the hand for the purpose of swinging the arm and operating the pumps.

Above each end of each cylinder 16 is a bracket 24, each bracket being fastened to the front wall of the casing 10 within the same and has a deflector 25 hinged thereto, these deflectors being hinged in such manner and position that when elevated as shown in Figs. 1 and 3, the openings 21 in the pump cylinders will be uncovered, but when turned downwardly into horizontal position the deflectors will overlie the openings and prevent the stream of water from the pump passing over the dishes. To operate these deflectors there are provided rods 26 connecting all of said deflectors and an operating extension 27 passes through a perforation in the end of the casing 10 and terminates in a ring 28 to be grasped by the fingers, which when pulled, will turn the deflectors into horizontal position as is evident.

In using this dish washing machine, the dishes to be washed are stacked within the casing 10 on each side of the stand 15 and around the same. Hot water is then poured into the receptacle until it covers the pump 110 cylinder. Due to the inclination of the bottom 12 of the receptacle, the water will all

run toward the lowest corner where the pump cylinders are situated and will maintain them submerged. The cover 11 will now be closed over the receptacle and upon manipulating the handle 23 by rocking it to and fro the pistons 19 will be moved from end to end of the pump cylinders and alternately draw the water into the cylinders and force it outward through the openings 21 in streams which will rise upwardly to the top of the receptacle and then fall downwardly upon the dishes. This operation being kept up for a suitable length of time, these streams of water will serve to thoroughly cleanse the dishes without the necessity of rubbing or handling them in any manner. When the water in the receptacle is to be removed it will only be necessary to withdraw the plug 30 from the outlet 31 in one side of the receptacle.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent, is:—

1. A dish washing machine comprising a receptacle having an inclined bottom, a pair of pump cylinders within the receptacle at the lowest part thereof, said pump cylinders being each pivoted at one end to the

receptacle and each having an opening through the top side thereof at each end, a piston within each of said pump cylinders, a swinging arm hinged to the side of the receptacle and pivotally connected to the pump pistons for operating the same, a handle without the receptacle connected to said swinging arm for imparting motion thereto, and a deflector adapted to be swung over each of said perforations in the cylinder to interrupt the flow of water to the dishes.

2. A dish washing machine comprising a receptacle, a pair of pump cylinders within said receptacle, each pivotally connected at one end to the receptacle, said cylinders each having an opening through the top at each end for the inflow and outflow of water, a piston within each of said cylinders, a swinging arm hinged to the wall of the receptacle and pivotally connected to the two pump pistons, a handle without the receptacle connected to said swinging arm for operating the latter, a bracket secured within the receptacle above each end of each of said pump cylinders, a deflector pivoted to each of said brackets and adapted to swing over an opening in a pump cylinder, connecting means between all of said deflectors for operating them in unison, and a rod extending through the end of the receptacle for operating the deflectors.

In testimony whereof I affix my signature in presence of two witnesses.

TOM WILLIAMS.
